UNITED STATES PATENT OFFICE.

WILLIAM K. KRAUSE, OF LOS ANGELES, CALIFORNIA.

PORTABLE COLLAPSIBLE TENT-HOUSE AND FOLDING BED COMBINED.

1,178,734.

Specification of Letters Patent. Patented Apr. 11, 1916.

Application filed April 12, 1915. Serial No. 20,959.

To all whom it may concern:

Be it known that I, WILLIAM K. KRAUSE, a citizen of the United States of America, residing at Los Angeles, county of Los Angeles, State of California, have invented a certain new and useful Portable Collapsible Tent-House and Folding Bed Combined; and I do hereby declare the following to be a full, clear, and exact description of the invention, such as will enable others skilled in the art to which it appertains to make and use the same.

This invention relates to portable collapsible tent-house and folding bed combined, and it may be said to consist in the provision of the novel and advantageous features and in the novel and improved construction, arrangement, and combination of parts as will appear from the description 20 and claims which follow hereinafter.

One object of the invention is to provide a novel and improved folding framework in combination with the folding bed frame.

Another object of the invention is to provide a novel and improved construction which permits of the tent-house and folding bed being compacted to occupy a comparatively small space, easily transported from place to place, set up for use or collapsed with a minimum amount of work and loss of time, and easily and quickly adjusted and manipulated to suit requirements in use.

Another object of the invention is to provide a novel and improved construction in which the bed clothes are not disarranged in folding the bed, and in which the more or less dusty exterior of the tent-house does not come in contact with any part of the 35 interior of the tent-house or bedding when the parts are collapsed and compacted.

Further objects of the invention are to provide a novel and improved construction of the nature specified which can be readily mounted on a vehicle, and is adapted to shut out insects and reptiles, and which by turning up the legs on the bed frame can be used as an ambulance, or as a covered sleeping berth which can be occupied while the vehicle is traveling from place to place.

Further objects of the invention are to provide a novel and improved construction of the nature specified which is simple and economical to manufacture, strong and durable, attractive in appearance, practical and serviceable, convenient and effective in

use, and which can be furnished at a comparatively low price to users.

Other objects and the advantages of the invention will be apparent to those skilled in the art from a careful consideration of the following description of the preferred form of the construction embodying the invention, taken in connection with the accompanying drawings in which—

Figure 1 is a broken side elevational view showing the combined tent-house and folding bed compacted and attached to a vehicle; Fig. 2 is a rear end elevational view of the same; Fig. 3 is a side elevational view showing the bed and tent-house set up; Fig. 4 shows the bed and tent-house in longitudinal section; Fig. 5 is a front end view of the tent-house, taken on the line 5—5 of Fig. 4 and showing the sides in raised position; Fig. 6 is an enlarged fragmentary cross-sectional view taken on the line 6—6 of Fig. 4; Fig. 7 is an enlarged broken sectional view taken on the line 7—7 of Fig. 5; Fig. 8 is an enlarged broken sectional view taken on the line 8—8 of Fig. 3; and Fig. 9 is an enlarged broken view showing one of the window fasteners.

The foldable bed frame consists of the front end cross-piece 10, the rear end cross-piece 11, and the side pieces 12 which are suitably secured to the cross-pieces 10 and 11 and are each divided into two parts joined together by hinges 13 disposed on the underside thereof.

The foldable framework of the tent-house consists of the front uprights 14 having the upper end portions thereof connected by crosspiece 15 and having the lower end portions connected by hinges 16 to the upper side of the forward end portions of the side pieces 12, the rear upright 17 having the lower end portions thereof connected by hinges 18 to the upper side of the rear end portions of the side pieces 12, and the upwardly and rearwardly inclined arms 19 which have the lower end portions thereof connected by hinges 20 to the upper end portions of the rear uprights 17 and which have on the upper end portions thereof the crossbar 21.

A bed spring 22 may be suitably mounted on the cross-pieces 10 and 11 and have arranged thereon the divided mattress 23 disposed between the side pieces 12 of the bed frame.

The uprights 14 and 17 may have thereon

suitable means such as the swinging arms 24 adapted to engage the stops 25 on the side pieces 12 to hold said uprights in erect position, and the bed frame may be supported at a suitable distance above the ground by legs 26 which have the upper end portions thereof mounted on pivots 27 on the side pieces 12, and adapted to bear against projections or abutments 28 on the side pieces 12.

To the rear of the cross piece 11 is a raised platform or floor 29 which is arranged at a lower level than the bed frame and is preferably provided with forwardly extending projections 30 adapted to fit in notches 31 or against projections with which the rear legs 26 may be provided.

The tent canvas or other suitable flexible fabric 32 for covering the bed frame, tent-house frame, and platform 29, is suitably secured to the crosspieces 10 and 11, and it extends downwardly from the crosspiece 11 and is suitably secured to the platform 29, and it may be formed to extend from the rear end of the platform 29 and over the crossbar 21 to the front end of the bed frame. But if desired the front end of the tent-house may be formed to provide thereon the hinged screen window 33, and the hinged windows 34 having light transmitting panes 35 and fasteners 36 for locking them in closed position. Also at the sides of the tent-house the covering fabric 32 may be attached to frames 37 which are mounted on hinges 38 secured to the tent-house frame and in closed position lie against the side pieces 12 and the uprights 10 and 11, but which can be raised and can be held in raised position by cords 38' if desired.

The rear end portion of the tent-house may be provided with a door 39 mounted on hinges 40 secured to one of the rear uprights 17 and having the lower end thereof at a suitable distance above the platform 29, and said rear end portion may also be provided with a ventilating door 41 mounted on hinges 42 secured to one of the arms 19.

Ropes, cables, or the like, 43, for supporting and holding the tent-house rigid, have one end portion thereof suitably attached to studs or projections 44 on the sides of the rear ends of the bed frame and the platform 29, and have the other end portion thereof looped around studs 45 at the top of the front uprights 14 and attached to studs 48 on any relatively stationary object such as the vehicle 47 on which the combined tent-house and bed may be mounted if desired.

In order to mount the combined tent-house and bed on the vehicle 47 any suitable or approved means may be employed, that shown consisting of angle plates 49 suitably secured to the crosspiece 10 on the front end of the bed frame and having thereon ex-

tensions 49 the lower ends of which are fitted on the bolts 50 on the rear ends of the vehicle springs 51; said extensions 49 being also connected to the body of the vehicle 47 by means of the brace bars 52.

From the foregoing the manner of use and the advantages of the construction will be readily understood by those skilled in the art, and it will be seen that the construction is well adapted to accomplish the objects of the invention. The bottom of the tent-house is raised above the ground and the tent-house is constructed to permit of shutting out flood water, reptiles, and insects, and to permit of occupants standing erect in the rear portion of the tent-house. By turning up the legs 26 the tent-house can be transported set up, and can be used as an ambulance or traveling sleeping berth. When desired the tent-house can be partially collapsed to make it smaller and warmer for the occupants, by first disengaging the arms 24 on the uprights 17 from the stops 25, then turning down the arms 19, and then piling the rear end portion of the tent-house on the forward portion, and again bringing said arms 24 into engagement with said stops 25. The tent-house can be completely collapsed and compacted to occupy a comparatively small space, by first disengaging the arms 24 on the uprights 17 from the stops 25, then turning down the arms 19, then piling the rear portion of the tent-house on the forward portion, then turning the uprights 17 and arms 19 down toward the bed frame, then turning up the legs 26 and pressing up on the bed frame to fold the latter, then pressing the collapsed parts toward the front uprights 14 and securing the whole in compacted condition by means of the ropes 43 and a tie plate 53 removably attached to said ropes.

The construction which has been particularly illustrated and described admits of changes and modifications and some of the parts thereof can be used without others—wherefore the right is reserved to all such changes and modifications as do not depart from the spirit and scope of the invention which is defined in the appended claims.

I claim:

1. In a construction of the nature specified, the combination of a foldable bed frame, legs pivotally mounted thereon, front and rear uprights on the bed frame, hinges connecting said uprights to the bed frame, arms extending upwardly and rearwardly from the rear uprights, hinges connecting said arms to the upper portion of the rear uprights, a crossbar on said arms, means for holding the uprights in erect position, a raised platform disposed at the rear of and at a lower level than the bed frame, and a covering fabric arranged to cover the uprights, bed frame, crossbar, and platform.

2. In a construction of the nature specified, the combination of a foldable bed frame, a foldable framework mounted thereon, a platform, a covering fabric arranged to cover the bed frame, framework, and platform, and means for mounting the whole on a vehicle.

3. In a construction of the nature specified, the combination of a foldable bed frame comprising a front end crosspiece, a rear end crosspiece, side pieces secured to the crosspieces and each divided into two parts, and hinges on the underside of the side pieces joining the parts; pivoted legs on the bed frame, a foldable framework comprising uprights mounted on the front end of the bed frame, a crosspiece between the upper ends of said uprights, uprights hinged on the rear end of the bed frame, arms hinged on the upper ends of the last mentioned uprights and extending upwardly and rearwardly, and a crossbar on said arms; a platform disposed at the rear of and at a lower level than the bed frame, a covering fabric arranged to cover the bed frame, framework, and platform, and means for mounting the whole on a vehicle.

4. In a construction of the nature specified, the combination of a foldable bed frame, a foldable framework mounted thereon, a platform, a covering fabric arranged to cover the bed frame, framework, and platform, pivoted legs on the bed frame,

and means for holding the framework rigid in set up condition.

5. In a construction of the nature specified, the combination of foldable bed frame, a foldable framework mounted thereon, a platform, a covering fabric arranged to cover the bed frame, framework, and platform, and frames hinged on the sides of said framework for raising the covering fabric adjacent thereto.

6. In a construction of the nature specified, the combination of a foldable bed frame, a foldable framework mounted thereon, a platform, pivoted legs on the bed frame, a covering fabric arranged to cover the bed frame, framework, and platform, frames hinged on the sides of said framework for raising the covering fabric adjacent thereto, and means for holding the framework rigid in set up condition.

7. In a construction of the nature specified, the combination of a foldable bed frame, pivoted legs thereon, a foldable framework mounted on the bed frame, framework, and platform, a vehicle, means for mounting the whole on the vehicle, and ropes connected to the vehicle and to the framework, bed frame, and platform.

In testimony whereof, I have signed my name to this specification at Los Angeles, county of Los Angeles, State of California, this 3rd day of April, A. D. 1915.

WILLIAM K. KRAUSE.
